BODY CONSTRUCTION

Alexander Benzick, Milwaukee, Wis., assignor to
 Nash-Kelvinator Corporation, Kenosha, Wis., a
 corporation of Maryland

Application May 23, 1941, Serial No. 394,774

4 Claims. (Cl. 296—28)

This invention relates to body construction and has particular reference to a window frame and regulator panel for an automobile body. More particularly the invention has reference to the window frame and regulator panel for the rear side window or rear quarter window of a sedan or coach type body.

It is an object of this invention to provide a window frame and regulator panel which will cooperate with the outer rear quarter panel of the body to form a rigid window frame.

It is another object of this invention to provide a window frame and regulator panel which will cooperate with the outer rear quarter panel of the body to form a door post of generally box-shaped cross section.

It is another object of this invention to provide a window frame and regulator panel which will cooperate with the outer rear quarter panel and wheel house to form a mutually reinforcing body structure.

It is another object of this invention to provide a panel having a window frame section and a regulator supporting section which will be cheaper to construct and assemble in an automobile body than the corresponding structure used heretofore.

Other objects and advantages of this invention will be apparent from a consideration of the following description and claims and the attached drawings, of which there are four sheets, and in which—

Figure 1 represents an elevational view of a right rear window frame and regulator panel as viewed from the inside of an automobile;

Figure 2 represents an elevational view of an outer right rear quarter panel of an automobile body as viewed from the inside of the automobile;

Figure 3 represents an elevational view of the panels shown in Figures 1 and 2 as they will be joined together in an automobile and viewed from the inside of the automobile;

Figure 4 represents a sectional view taken along a plane indicated by the line 4—4 in Figure 3 and looking in the direction of the arrows;

Figure 5 represents a sectional view taken along a plane indicated by the line 5—5 in Figure 3 and looking in the direction of the arrows;

Figure 6 represents a sectional view taken along a plane indicated by the line 6—6 in Figure 3 and looking in the direction of the arrows;

Figure 7 represents a sectional view taken along a plane indicated by the line 7—7 in Figure 3 and looking in the direction of the arrows;

Figure 8 represents a sectional view taken along a plane indicated by the line 8—8 in Figure 3 and looking in the direction of the arrows; and
 Figure 9 represents an end elevational view of the front edge of the outer quarter panel of the body.

The outer panel 50 of the body to which the window frame and regulator panel is arranged to be attached is shown in Figure 2. The panel 10 is provided with a window frame section 51 positioned over a side panel section 52, each of which merge into a section 53 which extends downwardly along the back of the automobile and is provided with a flanged edge 54 against which 15 a rear deck lid (not shown) is adapted to be seated. The window frame section 51 defines a window opening 55. The upper edges of the window frame section 51 and the section 53 are provided with a flat inwardly extending flange 56 from the inner edge of which a generally vertical flange 58 is turned upwardly. The flat flange 56 forms a base and anchorage for a mating flat flange 60 turned inwardly from the lower edges 20 of a roof panel 62 (see Figures 4, 8 and 9). A molding or gutter strip 64 may be positioned between the roof flange 60 and the horizontal flange 56. The upstanding flange 58 functions to center the roof panel 62 on top of the horizontal flange 56 and a corresponding flange on 25 the opposite side of the body. The flanges may be joined by the usual spot welding process well known to automobile body builders.

The side portion 52 of the outer panel is pressed inwardly to form a wheel house 66 around the 30 edges of which is formed a generally curved flat area 68 which defines apertures 70 through which bolts can be passed to attach the flange of a fender (not shown) to the quarter panel.

The forward edge of the quarter panel is folded 40 inwardly in a generally transversely extending flange as at 72 (see Figures 2 and 9), which flange is stepped as at 74 to receive suitable sealing strips (not shown) against which a door (also not shown) may abut when closed. The flange 45 72 is also provided with a recessed pocket at 76 within which a suitable keeper for the door locking mechanism may be secured by means of bolts passed through the holes 78. Tabs or fingers 80 project inwardly of the flange 72 and are used for a purpose to be described presently.

The lower portion of the flange 72 at the forward edge of the rear quarter panel 50 is curved 50 forwardly as at 90 (see Figures 2 and 3) and formed into a generally flat tab 92 which may be welded or otherwise suitably secured to a body

sill member (not shown). The lower ends of the stepped portions 74 of the flange 72 also curve forwardly as at 94 and merge into the main body of the flange 72 and the tab 92. The bottom edge of the quarter panel 50 forwardly 5 of the wheel house section 66 is provided with an outwardly curved roll 96 from the bottom edge of which a flat flange 98 is turned inwardly of the body. The flange 98 is arranged to be welded to the sill member of the automobile (not shown).

Around the window opening 55, the edges of the quarter panel are formed into window reveals 82, the inner edges of which are turned outwardly from the window opening into a flat annular flange 84 positioned in the plane of the opening. From the outer edges of the flange 84 a flange 86 is turned inwardly of the panel along the top and sides of the window opening (see Figures 2, 5 and 6). The flange 86 is broken at 10 intervals about the window opening as indicated at 88 (see Figure 2) so that it may be formed without tearing the metal from which the panel is stamped. The flange 86 is omitted along the bottom of the window opening to leave a slot 89 (see Figure 4) through which the window glass (not shown) may extend.

The window frame and regulator panel 100 which is arranged to cooperate with the rear quarter panel 50 just described is most clearly 30 shown in Figures 1 and 3 and consists of a window frame section 102 and a regulator panel section 104. The window frame section 102 defines an opening corresponding to the window opening 55 in the rear quarter panel and is provided with a flange 106 which is turned outwardly of the body and extends completely around the window opening. The outer edge of the flange 106 is flanged inwardly toward the center of the window opening as at 108. The outer edge of the flange 106 and the in-turned flange 108 are arranged to rest against the angle formed by the flanges 84 and 86 formed on the window frame section 51 of the rear quarter panel 50. The two panels are arranged to be secured together as by welding around the top and sides of the window opening 55.

The top edge of the window frame section 102 is provided with a series of outwardly pressed bosses 110 which are apertured to receive attaching means for the head lining of the vehicle (not shown).

The forward edge of the window frame panel 100 is formed into a channel shaped rib 112, the forward edge of which is arranged to abut against and be welded to the rear side of the flange 72 formed on the front of the rear quarter panel 50. Attention is called to the fact that the channel section 112 opens inwardly of the automobile and that the tabs 80 formed on the inner edge of the flange 72 project beyond the edge of the channel section 112 so that they may be bent over as indicated by the dotted lines in Figure 6. The channel section 112 is arranged to receive a tacking strip of wood or tightly rolled paper (not shown) which will be held in place by bending over the tabs 80. The tacking strip is used to secure the interior fabric trim of the body (not shown) which is attached to the tacking strip by means of tacks.

The regulator panel section 104 of the window frame 100 extends generally vertically downward below the window opening and is provided with a longitudinally extending rib 114 just be-

low the window opening and a series of rectangular stiffening ribs 116 which function to make the regulator panel more rigid. If desired, the metal within the rectangular ribs 116 may be cut away as at 118 to lighten the panel. Parallel ribs 120 are pressed in the regulator panel section 104 to add rigidity to the panel at the point where the window regulating mechanism is attached.

The regulator section 104 further defines an opening 122 arranged to receive an ash tray and a circular opening 124 through which the window crank shaft is arranged to project. Suitable supports (not shown) for the window glass and regulating mechanism can be attached to the regulator panel 104 by means of bolts passed through the holes 126 formed in the strengthening rib 120. Slots 127 are formed near the lower edge of the regulator section to receive and support suitable lugs formed on an arm rest bracket (not shown).

Towards its rearward edge and along the bottom thereof, the regulator section 104 is turned inwardly of the automobile in a curved flange 128 which is arranged to rest on and be secured to the inner surface of the wheel house panel 66 of the rear quarter panel 50. The forward edge of the regulator section 104 is provided with an outwardly offset flange 130, the purpose of which will be described presently. Attention is called to the fact that the flange 130 is spaced backwardly from the forward edge of the window frame section 102 and the channel section 112.

35 The lower portion of the window frame section 102 which defines the lower edge of the window opening is turned outwardly of the panel 100 in a flat flange 132, the outer edge of which is turned downwardly in a marginal flange 134. 40 Attention is called to the fact that the cutturned flange 132 at the bottom of the window frame section 102 is shorter than the flange 106 formed along the top and sides of the window frame section 102. A slot is thus left between the 45 rear quarter panel 50 and the window frame and regulator panel 100 along the lower edge of the window opening through which the window glass (not shown) is slidable. The out-turned flange 132 at the bottom of the window opening is provided with a pair of raised portions 136 over which the lower edge of a garnish molding (not shown) may be hooked to complete the interior of the automobile after the upholstery has been secured in place.

50 Attention is called to the fact that the top portion of the window frame section 102 is offset inwardly from the plane of the lower part of the window frame section 102 as indicated by the fold lines at 138. This is provided so that a fabric covered trim panel can be positioned 55 against the inside of the regulator section 104 and the forward column of the window frame section 102 and lie flush with the top of the window frame section 102.

60 65 When the window frame and regulator panel 100 is joined to the rear quarter panel 50, the forward column of the window frame section 102 will combine with the forward edge of the rear quarter panel 50 to form a door column of hollow 70 generally rectangular cross section (see Figure 6). Below the forward column of the window frame section 102 and just forwardly of the forward edge of the regulator section 104 a door column reinforcing member 140 (see Figures 3 and 7) is attached as by welding to the forward flange

72 of the rear quarter panel. The forward edge of the reinforcing column 140 is shaped into a channel section 142 which forms a continuation of the channel section 112 at the forward edge of the window frame section 102. The outwardly offset flange 130 on the forward edge of the regulator section 104 is arranged to fit behind and be welded to the rear edge of the reinforcing column 140. Below the regulator section 104 the column 140 is provided with an outwardly turned flange 144 which extends downwardly to the inwardly turned flange 98 at the bottom of the rear quarter panel 50.

A curved inwardly turned flange 128 at the lower rear edge of the regulator panel 100 is secured as by welding along the top surface of the wheel house 66 as was explained above and a separate strip 146 of angle shaped cross section is also welded to the wheel house panel 66 and extended forwardly and downwardly from the flange 128. The angle member 146 forms an abutment behind which a rain board (not shown) may be positioned to prevent water which may leak past the lower edge of the window and between the regulator section 104 and rear quarter panel 50 from soaking through the interior upholstery of the automobile. It will be noted that the lower edge of the regulator section 104 is pressed outwardly as at 148 and 149 so that the rain board will rest flush with the main surface of the regulator section 104.

The rear edge of the regulator section 104 is supported by a generally vertical brace 150 which is welded along the rear edge of the regulator section 104. The bottom of the brace 150 is provided with an inwardly turned flange 152 (see Figure 8) which is welded to the inside surface of the wheel house section 66 and an upwardly extending end 154 which extends to the top of the top portion 53 of the rear quarter panel. An 40 inturned flange 156 and a vertical flange 158 are provided on the top of the upwardly extending end 154 of the brace 150 so that the brace may be secured as by welding to the flange 56 formed on the upper edge of the top portion 53. The upwardly extending portion 154 of the brace 150 is stamped into a channel shaped cross section as at 160 to increase its rigidity.

The rear edge of the brace 150 along the bottom half thereof is turned inwardly in a flange 162 to which a gusset plate 164 is attached by means of screws 166. The gusset plate 164 has a rearwardly extending flange 168 turned backwardly from the edges thereof and is provided with strengthening ribs 170 and lightening knock out apertures 172. The upper edge of the gusset plate 164 forms a support for a rear shelf 174 along the forward edge of which is formed a flange 176. The flange 176 is hooked over the top of the gusset plate 164 and secured thereto as by means of screws 178. The side edges of the shelf 174 are stamped into channel shaped cross section as at 180 to increase the rigidity of the shelf.

A window guide bar 182 (see Figures 3 and 8) of generally Z-shaped cross section has its inner flange secured as by welding to the outer surface of the regulator panel 104 and the brace 150. The guide bar 182 extends downwardly and backwardly from the rear edge of the slot 88 between the window frame section 102 and the rear quarter panel 50 along the line of the edge of the window pane. A similar guide bar 184 is provided along the forward edge of the window pane. The guide bars 182 and 184 serve as supports for

window run channels (not shown) of any desirable form.

It should thus be apparent that the combined window frame and regulator panel just described 5 may be formed as a single stamping from sheet metal of proper thickness and that the single stamping will function to support window regulating mechanism, window guide bars, upholstery trim wire, window molding and suitable ash trays 10 or accessories. The stamping further cooperates with the rear quarter panel to form a window and door post of hollow cross section which is both light and rigid and is also attachable to the wheel house section of the rear quarter panel to further interbrace the rear quarter panel with the inner window frame and regulator panel. The stamping thus disclosed eliminates many 15 steps in assembling the automobile body and is easily and cheaply manufactured. Obviously 20 the structure disclosed and described may be altered in many respects to meet the individual needs of various users without departing from the spirit of the invention. The structure is 25 equally applicable to automobile bodies of the sedan type and to bodies having a different arrangement of the outer rear quarter panel. This disclosure should be taken as an example only and not as a limitation of my invention, to which I make the following claims:

1. In an automobile body having an outer panel defining a window opening and having an inwardly extending flange along the forward edge thereof, a window frame and regulator panel comprising a stamping having an upper portion defining a window opening registering with the window opening in said outer panel, a regulator portion positioned below said window opening portion and arranged to support window regulating mechanism, flanges turned outwardly of said body around the inside of the opening in said upper portion, the flange at the bottom of said window opening being narrower than the flange along the top and sides of said window opening portion, inwardly extending flanges formed on 40 said outer panel arranged to be secured to said outwardly extending flanges along the top and sides of said opening in said upper portion, a flange having a channel shaped cross section formed on the forward edge of said upper opening portion and secured to said inwardly extending flange of said outer panel, a flange formed on the forward edge of said regulator supporting portion and offset to the rear of said inwardly extending flange of said outer panel, and a reinforcing column having a flange of channel shaped cross section along its forward edge secured to 50 said inwardly extending flange on said outer panel and forming a continuation of said channel shaped flange on said window opening portion, 55 said flange on said regulator portion being secured to the rear edge of said reinforcing column.

2. Automobile body construction comprising an outer panel defining a window opening and having an inwardly extending flange along the forward edge thereof, a flange turned inwardly from 60 said outer panel along the top and sides of said window opening, an inner panel defining a second opening registering with said opening in said outer panel, flanges turned outwardly of said inner panel around the top and sides of said second opening and secured to said inwardly turned flanges on said outer panel, a flange of inwardly opening, channel shaped cross section formed along the forward edge of said inner panel opposite said second opening and secured to said in-

wardly extending flange along the forward edge of said outer panel, an edge formed on said inner panel below said channel shaped flange and offset to the rear thereof, and a reinforcing column having a channel shaped flange formed along the forward edge thereof and secured to said inwardly extending flange of said outer panel in continuation of said channel shaped flange on said inner panel, the rear edge of said reinforcing column being secured to said offset edge of said inner panel, said reinforcing column extending below said inner panel.

3. Automobile body construction comprising an outer panel defining a window opening and having a flange turned inwardly of the body along its forward edge, an inner panel defining a second opening registering with the opening in said outer panel and having a flange of inwardly opening, channel shaped cross section formed along the upper part of its forward edge, the lower part of the forward edge of said inner panel being offset to the rear of said channel shaped flange, and a reinforcing column having a flange of channel shaped cross section formed along its forward edge, said reinforcing column being secured along a portion of its rear edge to said offset edge of said inner panel and along

its entire forward edge to said inwardly turned flange on said outer panel, said channel shaped flanges of said reinforcing column and said inner panel forming a continuous channel along said inwardly extending flange on said outer panel.

4. Automobile body construction comprising an outer panel defining a window opening and extending therebelow, inwardly extending flanges formed on the forward edge and bottom of said panel, an inner panel defining a second opening 10 registering with said opening in said outer panel and extending therebelow but terminating above said flange on the bottom of said outer panel, said inner panel having the upper portion of its forward edge secured to said inwardly extending flange on said outer panel and the lower portion of its forward edge spaced to the rear of said last mentioned flange, and a reinforcing column 15 having its forward edge secured to said inwardly extending flange on said outer panel and extending below said inner panel to said inwardly turned flange along the bottom of said outer panel, the lower portion of the forward edge of said inner panel being secured to the rear edge of said reinforcing column.
